UNITED STATES PATENT OFFICE.

WINTWORTH W. DUKESHIER, OF KANSAS CITY, KANSAS, ASSIGNOR OF TWENTY-THREE ONE-HUNDREDTHS TO JOHN DUKESHIER AND TWENTY-THREE ONE-HUNDREDTHS TO FRED CLAUSIN, BOTH OF KANSAS CITY, KANSAS.

PROPELLER.

1,273,751.

Specification of Letters Patent. Patented July 23, 1918.

Application filed June 1, 1917. Serial No. 172,302.

To all whom it may concern:

Be it known that I, WINTWORTH W. DUKESHIER, a citizen of the United States, residing at Kansas City, in the county of Wyandotte and State of Kansas, have invented certain new and useful Improvements in Propellers; and I do hereby declare the following to be a full, clear, and exact description of the invention, such as will enable others skilled in the art to which it appertains to make and use the same.

This invention relates to propellers and more particularly to devices for varying the angle of the blades for varying the speed and pulling power of the article propelled and also for reversing the direction thereof.

An object of the invention is the provision of an improved and simple structure for engaging and rotating stub shafts on which are mounted the blades of the propeller, so that the angle of the blades can be varied to reverse the direction of the article being propelled.

A further object of the invention is the provision of safety latches under the control of the operator of the article being propelled for positively locking the blades in any desired position so that accidental movement thereof is eliminated.

With these and other objects in view, the invention consists in the novel construction, arrangement and formation of parts as will be hereinafter specifically described, claimed and illustrated in the accompanying drawings, forming a part thereof, in which:

Figure 1 is a side elevation of the improved propeller and mechanism for varying the angle of the blades.

Fig. 2 is a vertical longitudinal section through the improved propeller and the mechanism for varying the angle of the blades thereof.

Fig. 3 is a transverse sectional view taken on the line 3—3 of Fig. 2.

Fig. 4 is an end elevation of the hub of the propeller showing the removable end wall.

Fig. 5 is a transverse sectional view on the line 5—5 of Fig. 2.

Fig. 6 is a transverse sectional view on the line 6—6 of Fig. 2.

Fig. 7 is a transverse section on the line 7—7 of Fig. 2 taken through the shaft, and

Fig. 8 is a detail perspective view showing one end of the locking latches.

Referring to the drawings in detail, wherein similar reference numerals designate corresponding parts throughout the several views, the numeral 1 generally indicates the improved propeller, which includes the rectangular hollow hub 2 and the hollow shaft 3 rigidly secured thereto, which extends to any suitable type of prime mover (not shown). The hollow shaft 3 is journaled in suitable supports 4, which are secured by suitable fastening elements to the floor of the article to which the improved propeller is attached and the shaft 3 is prevented from moving longitudinally on the supports 4 by collars 5 carried by the shaft 3 and engaging the outer faces of the supporting brackets 4.

Each side face of the hollow hub 3 is provided with a centrally disposed thickened projecting stud 6 having an aperture extending therethrough communicating with the interior of the hub and in which is journaled a stub shaft 7 having a pinion 8 keyed to its inner end and a collar 9 to hold the pinion in its correct position on the stub shaft. Pinions 8 bear against the inner surfaces of the side faces of the hollow hub 3 and limit the outward movement of the stub shafts.

A blade 10 having an inner hollow spoke 11 is secured on the end of each stub shaft 7 for rotation therewith, by means of removable fastening elements 12. A rack bar 13 is provided for each pinion 8 and is in mesh therewith and is slidably mounted in a guide 14 formed in each corner of the hollow hub. The guides 14 are formed by enlarging and striking out the corners of the hub 3 as at 15. The inner ends of the rack bars 13 are bent inwardly as at 16 and are connected to the hollow shifting rod 17 which is slidably mounted in the hollow shaft 3. The hollow shaft 3 is slotted as at 18 and slidably receives a pin 18, which passes through and is rigidly secured to the hollow shifting rod 17 adjacent the free end thereof and has its ends rigidly connected to a sleeve 19. The sleeve 19 has an annular groove 20 which slidably receives the inwardly extending pins 21 removably carried by the sliding adjusting sleeve 22. The adjusting sleeve 22 has a downwardly extending lug 23 having

ing a base 24 secured thereto and the lug 23 is slidably mounted in the groove 25 formed in a guide 26 and prevents the adjusting sleeve 22 from rotating with the shaft 3.

An adjusting lever 27 is provided for shifting the adjusting sleeve 22 and is pivotally secured intermediate the ends of the arcuate rack bar 28 to the lug 29. A connecting link 30 is pivotally secured to the adjusting sleeve 22 and the shifting lever 27 and upon movement of the lever 27 the blades 10 can be adjusted to any angle desired. A sliding pawl 31 is provided for engaging the arcuate rack bar 28 for locking the lever 27 in any set position and has a suitable pivoted handle 32 and connecting rod 33 to operate the same.

To positively lock the blades 10 in any set position and to take the strain off of the rack bars 13, a safety latch 34 is provided for each pinion 8 to prevent the rotation thereof. The safety latches 34 have their forward ends provided with a tooth 35 for engaging between the teeth of the pinion 8 and thus prevent the rotation thereof. The inner ends of the latches 34 are bent inwardly as at 36 and connected to an adjusting rod 37 which is slidably received in the hollow adjusting rod 17. The free end of the adjusting rod 37 extends into the hollow shaft 3 beyond the end of the shifting rod 17 and rigidly carries a pin 38 which extends through a slot 39 in the hollow shaft 3. The terminals of the pin 38 are rigidly secured in the sleeve 40 slidably mounted on the hollow shaft 3, which has an annular groove 41 formed therein which slidably receives the pins 42 removably carried by the shifting sleeve 43 rotatably mounted upon the sleeve 40. A lug 44 similar to the lug 23 is slidably mounted in the groove 45 formed in a guide 46 and prevents the shifting sleeves 22 and 43 from rotating with the shaft 3. The shifting rod 37 is provided with a slot 37^a through which extends the pin 18 carried by the shifting sleeve 22 and this slot 37^a allows the hollow shifting rod 17 to be moved without moving the hollow shifting rod.

A shifting lever 47 similar to the shifting lever 27 is pivotally secured to the lug 48 intermediate the ends to an arcuate rack bar 49, which receives a sliding pawl 50 controlled by a handle 51 and a connecting rod 52 and the lever 47 serves to adjust the safety latches 34 in or out of engagement with the pinions 8, and the pawl 50 serves to hold the latches 34 in locked or unlocked position.

A removable end wall 53 is provided for the hollow hub 2 so that access may be readily had to the interior of the hub when necessary. The end wall 53 is slidably mounted in guides 54 formed by bending the free ends of the side walls of the hub up-

wardly and then downwardly and has an operating handle 55 formed thereon, so that the same can be readily removed. The end wall 53 is held against accidental movement by suitable fastening means (not shown.)

In operation of the improved device, the shifting lever 47 is pushed away from the hub 2, which draws the safety latches 34 through the medium of the shifting rod 37 out of engagement with the pinions 8 and 75 then the blade shifting lever 27 is moved in the direction desired which will turn the stub shafts 7 through the medium of the racks 13, the pinions 8 and the sliding hollow shifting rod 17, and when the desired 80 angle of the blades is reached, the shifting lever 27 is released and the pawl 31 is allowed to engage the arcuate rack bar 28 and then the safety latches 34 are thrown in engagement with the pinions 8 to positively 85 prevent movement thereof.

In practice, I have found that the form of my invention, illustrated in the accompanying drawings and referred to in the above description, as the preferred embodiment, is the most efficient and practical; yet realizing the conditions concurrent with the adoption of my device will necessarily vary, I desire to emphasize the fact that various minor changes in details of construction, 95 proportion and arrangement of parts, may be resorted to, when required without sacrificing any of the advantages of my invention, as set forth.

What is claimed is:—

1. In a device of the class described, a hollow hub, a hollow shaft connected to the hub and extending rearwardly therefrom, stub shafts extending radially from and rotatably mounted in the hollow hub, blades 105 carried by the outer terminals of the stub shafts, pinions mounted on the inner terminals of the stub shafts, means slidably mounted in the hollow shaft for rotating the pinions to vary the angle of the blades, 110 and means for engaging the pinions to prevent rotation thereof.

2. In a device of the class described, a hollow hub, a hollow shaft connected to the hub and extending rearwardly therefrom, stub shafts extending radially from and rotatably mounted in the hollow hub, blades carried by the outer terminals of the stub shafts, pinions carried by the inner terminals of the stub shafts, rack bars slidably mounted in the hollow hub and meshing with said pinions, said rack bars having their inner terminals connected together, and a shifting rod slidably mounted in the hollow shaft and connected to the inner 120 terminals of the rack bars for rotating the pinions to vary the angle of the blades.

3. In a device of the class described, a hollow hub, a hollow shaft connected to the hub and extending rearwardly therefrom, 125

stub shafts extending radially from and rotatably mounted in the hollow hub, blades carried by the outer terminals of the stub shafts, pinions carried by the inner terminals of the stub shafts, rack bars slidably mounted in the hollow hub and meshing with said pinions, said rack bars having their inner terminals connected together, a shifting rod slidably mounted in the hollow shaft and connected to the inner terminals of the rack bars for rotating the pinions to vary the angle of the blades, and locking latches slidably mounted in the hub for engaging the pinions to prevent rotation thereof.

4. In a device of the class described, a hollow hub, a hollow shaft connected to the hub, stub shafts extending radially from

and rotatably mounted in the hub, blades carried by the outer terminals of the stub shafts, pinions carried by the inner terminals of the stub shafts, rack bars slidably mounted in the hub and meshing with the pinions, a hollow shifting rod slidably mounted in the hollow shaft and connected to the inner terminals of the rack bars, sliding latches adapted to engage the pinions to prevent rotation thereof, and independent means for operating the rack bars and the locking latches.

In testimony whereof I affix my signature in presence of two witnesses.

WINTWORTH W. DUKESHIER.
